EGG CARRIER

Filed Aug. 9, 1926

2 Sheets-Sheet 2

UNITED STATES PATENT OFFICE.

JOHN E. WALSH, OF CHICAGO, ILLINOIS.

EGG CARRIER.

Application filed August 9, 1926. Serial No. 128,034.

My invention relates to egg carriers and has for its main object the provision of a simple, inexpensive and efficient egg carrier of the knock-down type.

5 One of the objects of my invention is the provision of a carrier of this character, which may be shipped to the egg market, where the eggs are to be put up, packed or crated, for sale, in flat folded form and 10 which may be quickly and conveniently set up in egg carrying form as and when it is to be used.

Another object of my invention is the provision of a novel carrier comprising a filler 15 structure and a wrapping sheet, both made of cardboard or the like, one end of the wrapping sheet being made to cooperate with the filler structure and to serve as a partition for the egg cells therein, while the 20 opposite end of the wrapping sheet is made to interlock with the filler structure and the first named end for securing the carrier in closed position.

Other objects will appear hereinafter.

25 The invention consists in the combinations and arrangements of parts hereinafter described and claimed.

The invention will be best understood by reference to the accompanying drawings 30 forming a part of this specification, and in which,

Fig. 1 represents a perspective view showing my improved carrier as it appears when set up in egg carrying form with the wrapping sheet secured in closed position;

35 Fig. 2 is a cross section taken on the line 2—2 of Fig. 1;

Fig. 3 is a longitudinal section taken on the line 3—3 of Fig. 2;

40 Fig. 4 is a plan view showing the carrier as it appears when in knock-down form, with the wrapping sheet spread out and the filler structure folded thereon;

Fig. 5 represents a plan view of the wrapping sheet detached from the filler structure;

45 Fig. 6 is a plan view of one of the cross strips; and,

Fig. 7 is a fragmentary view showing the cellular structure as it appears when set-up 50 on the end of the wrapping sheet.

The preferred form of construction as exemplified in the accompanying drawings comprises two side strips 8 and 9 and an intermediate partition section 10, arranged 55 in parallelism and intersected by cross strips 11 to produce a filler or cellular structure

having on one side of the intermediate partition section 10 a row of egg holding cells 12 and having on the opposite side of said intermediate partition section a similar row 60 of egg holding cells 13.

The cellular structure, thus composed of the side strips 8 and 9, intermediate partition section 10 and intersecting cross pieces 11, is arranged to be collapsed for the shipment 65 or storage of the carrier in knock-down form. To this end, the cross pieces 11 at the places where they intersect the side strips 8 and 9 and the intermediate partition section 10, are provided with open slits or slots 14, slits 70 or slots 15 in alinement therewith and separated therefrom by integral webs 16. These cross pieces 11 are interengaged with the side strips 8 and 9 and also with the intermediate partition section 10 by applying the slits or 75 slots 14 thereof to the open elongated slits or slots 18 provided for the purpose in proper positions in said side strips 8 and 9 and in said intermediate partition section 10.

Now, the said elongated slits or slots are 80 made so as to have shoulder portions 19 located opposite relatively narrow necks 20; and the slits or slots 14 are so applied to the slits or slots 18 that the integral webs 16 are slipped through the narrow necks 20 to 85 be engaged over the shoulder portions 19. Under this construction, the filler or cellular structure is adapted to be swung upon intermediate partition section 10 into either knockdown form or set-up form. In Fig. 90 7 the cellular or filler structure is shown set-up on the intermediate partition section, while in Fig. 4 it is shown in knockdown form thereon with the cross pieces 11 and side strips 8 and 9 folded substantially flat 95 upon said intermediate partition section 10. To fold the cellular or filler structure from the set-up form shown in Fig. 7 into the knock-down form shown in Fig. 4, the side strip 9 is drawn endwise so as to protrude 100 over the one end of the partition section while the side strip 8 is moved endwise in the opposite direction so as to protrude over the opposite end of said partition section, the cross sections swinging upon the said partition section into substantially flat position thereon so that the side strip 9 will overlie said partition section while the side strip 8 will underlie the same.

According to an important feature of my 110 present invention, the intermediate partition section 10 is made integral with a wrapping

sheet 21, divided by corner folding lines as 55
22 into, first, the partition section 10, which
comes at one end as clearly shown in Fig. 5,
then into the successive sections 23, 24, 25, 26,
27 and 28. When it is desired to fill the
cells of the carrier with eggs, the partition
section 10 is turned upwardly as shown in
Fig. 7 and the cellular structure is set-up or
opened so that the row of cells 13 is closed
10 at the bottom by the section 23. After the
cells 13 have been filled with eggs, the wrapping
sheet is folded about the same so that
the section 25 is situated upon the top of the
structure, whereupon the structure with the
15 wrapping sheet is turned right side up with
the result that the said section 25 comprises
a bottom both for the eggs in the cells 13
and for the eggs to be inserted in the cells 12.
Having thus inserted the eggs in both rows
20 of cells 12 and 13, the wrapping sheet is
brought up over the top of the structure so
that the end section or portion 28 may be
entered in the open slits or slots 14 along
side of the intermediate partition section 10,
25 whereby the cellular structure is bound and
strengthened by the wrapper with the end
section 28 frictionally held along side the
partition section 10.

By making the carrier in this manner, the
30 use of wrapping paper, strings, clasps and
other securing devices are entirely eliminated.
When the carriers are in knock-down form,
they may be piled one upon the
35 other in vertical stacks and then bound in
bundles or suitably boxed for transportation
or storage. In knock-down form, therefore,
a large number of the carriers can be secured
together in compact arrangement so as to
occupy relatively small space.

40 In practice, the cellular or filler structure
may be set-up or opened on the partition section
10 in practically an instant by grasping
the wrapping sheet close to said partition
section 10 with the thumb and forefinger and
45 giving the wrapping sheet a quick jerk or
flick. By reason of this feature, my im-
proved carrier may be employed to advan-
tage where eggs are packed as candled, since
no time need be lost in putting together or
50 setting-up the carrier. For the same reason,
merchants who sell to the retail trade may
use this carrier to advantage. When the
wrapping sheet is secured in position, it will

be noted that the section 25 serves as the bot- 55
tom for the cells, that the sections 24 and
26 constitute the opposite sides and that the
sections 23 and 27 form the top cover for the
cells. From an inspection of Fig. 1, it will
also be observed that the cross pieces 11 pro- 60
trude a distance beyond the side strips 8 and
9 where they are engaged by the side sections
of the wrapping sheet; and further that the
side strips 8 and 9 together with the parti- 65
tion section 10 protrude beyond the cross
pieces which represent the ends of the cellular
structure.

While I have illustrated and described the
preferred form of construction for carrying
my invention into effect, this is capable of 70
variation and modification without depart-
ing from the spirit of the invention. I,
therefore, do not wish to be limited to the
precise details of construction set forth, but
desire to avail myself of such variations and 75
modifications as come within the scope of the
 appended claims.

Having described my invention, what I
claim as new and desire to secure by Letters
80 Patent is:

1. An egg carrier including a cellular
structure composed of side strips and cross
pieces collapsible into substantially flat form;
a partition interconnecting the cross pieces
85 and on which the side strips and cross
pieces are collapsible into substantially flat
form; and a wrapping sheet made integral
with said partition and separate from the
side strips and cross pieces, substantially as
90 described.

2. An egg carrier comprising side strips,
an intermediate partition strip, and a plu-
rality of cross pieces together forming open
cells, said strips, partition and cross pieces
being formed with shouldered slots whereby 95
they are interlocked and adapted to fold
upon the intermediate partition and said
intermediate partition being extended to
form a wrapping sheet adapted to extend
100 around the device to close said cell, said
wrapping sheet having an end section adapt-
ed to be inserted in the slots in the cross
pieces adjacent the intermediate partition,
substantially as described.

In testimony whereof I have signed my 105
name to this specification.

JOHN E. WALSH.
